[57] CLAIM

The ornamental design for an IV infusion controller, as
shown and described.

DESCRIPTION

FIG. 1 is a front elevational view of an IV infusion
controller embodying our new design;

FIG. 2 is a left side elevational view thereof;

FIG. 3 is a top plan view thereof;

FIG. 4 is a rear elevational view thereof;

FIG. 5 is a right side elevational view thereof; and

FIG. 6 is a bottom plan view thereof.

The broken line showing of the clamp in FIGS. 2
through 6 is for illustrative purposes only and forms no
part of the claimed design.
